[57] CLAIM

The ornamental design for twist-tie closure dispenser, as shown and described.

DESCRIPTION

FIG. 1 is a top, front, and left side perspective view of a twist-tie closure dispenser showing my new design;

FIG. 2 is a front elevational view thereof;

FIG. 3 is a top plan view thereof;

FIG. 4 is a rear elevational view thereof;

FIG. 5 is a bottom plan view thereof; and

FIG. 6 is a left side elevational view thereof, the right side being a mirror image of that shown.

The broken-line depiction of twist-tie closures in the views is for illustrative purposes only and forms no part of the claimed design.
